United States Patent Office

Des. 200,742
Patented Mar. 30, 1965

200,742

ELECTRONIC CALCULATOR

Moto Shimano, Los Angeles, and Delmar Everitt, Santa Susana, Calif., assignors to Friden, Inc., a corporation of California

Filed Mar. 10, 1964, Ser. No. 78,942

Term of patent 14 years

(Cl. D64—11)

FIG. 1

Des. 200,742

PAGE 2

FIGURE

FIG. 1 is a front view of the electronic calculator of our invention;

FIG. 2 is a perspective view showing the front, top, and left side of the machine of our invention; and

FIG. 3 is a perspective view showing the back, right side and top of the machine of our invention.

The dominant features of our design reside in those portions shown in full lines in the drawings.

We claim:

The ornamental design for an electronic calculator, as shown and described.
